UNITED STATES PATENT OFFICE.

ARNOLD J. TANNER, OF NORTH HAVEN, CONNECTICUT.

DISPLAY AND DISPENSING CONTAINER AND THE LIKE.

Application filed March 12, 1927. Serial No. 174,743.

The present invention relates to folding boxes or containers for merchandise and amongst several objects, one is to provide a container which may be assembled and set up for use with the least amount of labor and care. Another object is to provide a rigid shipping container which may be adapted for packing various kinds of merchandise. A further object is to design the container so that the goods contained therein can be dispensed therefrom one at a time, and in all instances the goods will be fully displayed with the utilization of the least amount of space on the store counter or elsewhere.

The improved container is composed of a single blank having a main or body portion and an extension therefrom. Said body portion is foldable so as to alone constitute the receptacle part of the container and the extension of the blank is foldable into the receptacle so as to form a lining or double wall for the back of the receptacle, and if required a lining for the bottom of the receptacle. Further if desired, the extension may be lengthened so as to form a partition within said receptacle. The extension in one form of the invention has, as an integral part a display card or portion cut therefrom which, when said extension is folded into the receptacle, stands above the back wall of the receptacle and further this display card or portion is foldable so as to form a cover for the open top of the receptacle. In another embodiment of the invention, the display card is a separate member which is adapted for use both as an advertising medium and as means for closing the open front of the receptacle.

The improved box is very simple in construction and consumes comparatively little material, but its efficiency is in no way decreased on account of its simplicity. Furthermore, the blank can be folded to form the container so that the printing is on one side only, which in itself is a considerable saving in the cost of production.

The novel features of the improved container will be more fully described herein-after with reference to the accompanying drawings wherein:

Figure 1 is a perspective view showing the complete container set up with contents therein;

Figure 2 is a plan view, on a reduced scale,

of the blank from which the container is constructed;

Figure 3 is a sectional view, slightly enlarged, of the container shown in Figure 1;

Figure 4 is a sectional view showing a modified form of the improved container, and

Figure 5 is a sectional view of another modification.

Referring to said drawings, the improved container in all the modified forms shown is composed of a blank having the body portion A and portion B extending upwardly therefrom. The body portion A is arranged to be folded to form the receptacle part of the container, and the portion B is arranged to form a lining or reenforced back and bottom for the receptacle in all modifications shown in the drawings. The back of the container has a cut-out portion C, which is arranged to stand in an angular position relatively to the back member when the latter is folded over.

Particularly describing the construction shown by Figures 1, 2 and 3, herein the body member A is provided with a folding flap 1 and tongues 2 which are arranged to be folded inwardly to form the bottom of the receptacle. It will be understood that the blank is first folded on the scored lines 3 and the end tab 4 is glued to the other end 5 of the blank. The body member is also folded on the scored lines 6 and in this way the receptacle part of the container is formed. The portion 7 of the body A forms the front of the container, and is cut away so to provide a partly open front. To reinforce the side edges of the opening, the folding flaps 7' are turned inwardly. The portion 8 forms the back of the receptacle and this portion has extending therefrom, at right angles thereto, the member B, which latter member is folded over and downwardly on the scored line 9. The extension member B is divided into a number of sections defined by creases or scored lines and which sections are designated by the reference letters a, b, c, d, e and f. When the blank is folded these sections form the various parts of the container and these parts are identified by the same reference letters as will be seen by reference to Figure 3. In this figure a forms the back of the display device or cover, b the front wall of said device, c is the lining at the back of

the receptacle, *d* is the lining for the bottom of the receptacle, *e* is the back wall of the partition and *f* forms the front wall of said partition.

- 5 The blank A, shown in Figure 2 is reduced in scale from the blank, of which the containers shown in the other figures of the drawing are constructed; but it will be understood that all the latter containers are 10 each composed of a blank of a substantially similar form. The back of the container, shown in Figures 1 and 3, is extended above the top edge of the receptacle to such a height, that when folded over, a suitable 15 cover is provided for the open top of the container; and to make the container complete and secure for shipping, a telescopic cover or sliding sleeve is placed over or around the container.
- 20 The double back forms means for rendering the container very rigid, and the part folded down into the receptacle provides a reenforced bottom, which carries the weight of the contents away from the bottom of the receptacle so that the tuck-in flap 1 will not open accidentally due to the weight of the contents pressing thereon. Furthermore, the folded portion of the member B 25 within the receptacle, forms a positive means for spacing the merchandise contained therein.

Referring to Figure 4 herein, the construction of the container is substantially the same as above described with the exception that in Figure 1, the double back or extension member C, is folded over to form a cover 12; and in that case a telescopic outer cover (not shown) would be employed with advantage to cover the container. In Figure 4, however, the back portion does not extend above the top line of the container, and in this instance it is possible to use with advantage the outer wrapper 13, which is passed completely around the container so that the turned down ends 14 meet at a central point, where they may be tucked downwardly between the contents of the container as shown in full lines and thereby a very efficient wrapper for the container is provided.

Figure 5 shows a modified construction wherein the main part of the container is substantially the same, but in this example the back of the container is not cut out to provide a display member C, instead the display member is provided as a separate part, in the form of a panel 16. The front of the container is cut away at 17, and to prepare the container for shipping the panel 16 is used to close the open front 17. When said panel is used as a display device it is positioned by engaging its reduced end in the slit 18 provided at the top of the double back wall of the container, and by this means the display device is held in an erect

position. The panel 16 thus serves both as a closure means and an advertising medium. With this form of container a flanged cover 19 is preferably employed to cover the open top of the container.

The improved container is delivered in a flat condition with the two ends 4 and 5 of the blank glued together. The first operation in setting up the container, is to fold the tongues 2 and then tuck in the flap 1 to form the bottom of the container. The extension member A is then folded on the several scored lines so as to form the double back and bottom of the container, and the partition in the receptacle is formed at the same time. Folding the blank in this manner is very simple and can be effected with a very few folding operations.

Obviously, modifications may be made in the details of construction of the invention heretofore described to adapt the container for various uses in packing different articles of different kinds; and it is to be understood that any modification coming fairly within the terms of the appended claims shall be covered thereby.

I claim—

1. A folding container as described having a body open at the top and front constituting a receptacle; an extension from the back wall of said body adapted to be folded into said receptacle to form a lining for said back wall; a separate removable panel forming a closure means for the open front of the container and means for supporting said panel at the back of the container to permit utilization thereof as a display card.

2. A folding container as described having a body open at the top and front constituting a receptacle; an extension from the back wall of said body adapted to be folded into said receptacle to form a lining for said back wall; a separate removable panel providing a closure means for the open front of the container, means in said back wall for supporting said panel to permit utilization thereof as a separate member for closing the open top of the container.

3. A folding container as described composed of a blank having a body portion arranged to be folded to alone form a complete receptacle; said receptacle being open at both the top and front; an extension from the back wall of said body adapted to be folded into said receptacle to form a lining for the back wall of the receptacle; a separable display member carried by said extension so as to be supported in an erect position above said receptacle, and said display member being adaptable for use as a closure means for the open front of the receptacle.

4. A folding container as described having a receptacle provided with an open top and front; an extension extending from the back wall of the receptacle adapted to be

folded into the receptacle to form a reinforcing lining for the back wall and bottom of the receptacle; a cover for the open top of the receptacle and a removable panel adapted to be employed as a closure means for the open front of the receptacle and as a display card for the container.

5. A folding box or container with an open top constructed of a single blank having a body foldable to form the back and front walls of the box; folding extensions 10 depending from said body providing means for closing the bottom of the box; said front

wall being cut out to form an inspection opening therein; a separate cover for closing 15 said top; a separate panel having a sliding engagement at the back of the front wall for closing the opening in said front wall, and means whereby said panel is supported in an upright position on said back wall so as 20 to operate as a display card.

Signed at New Haven, county of New Haven, State of Connecticut this 11th day of March, 1927.

ARNOLD J. TANNER.
